(57) **CLAIM**

I claim the ornamental design for a clutch bag, as shown and described.

DESCRIPTION

FIG. 1 illustrates a perspective view of the front of the clutch bag according to my design.

FIG. 2 is a direct view of the left side of the clutch bag, relative to FIG. 1.

FIG. 3 presents a view of the right side of the clutch bag, relative to FIG. 1.

FIG. 4 is a view of the bottom of the clutch bag, relative to FIG. 1.

FIG. 5 is view of the top of the clutch bag; and,

FIG. 6 is a plan view of the back of the clutch bag.
